Primary Examiner — Angela J Lee

(57) **CLAIM**

The ornamental design for a mount for electronic devices, as shown and described.

DESCRIPTION

FIG. 1 is a front, side, and top perspective view of a mount for electronic devices embodying the new design; FIG. 2 is a back, side, and top perspective view thereof; FIG. 3 is a front view thereof; FIG. 4 is a back view thereof; FIG. 5 is a top view thereof; FIG. 6 is a bottom view thereof; FIG. 7 is a first side view thereof; and, FIG. 8 is a second side view thereof. The broken lines depict portions of the mount for electronic devices in which the claimed design is embodied and form no part of the claimed design.
